J. King.

Rotary Church.

No 85,594.

Patented Jan. 5, 1869.

JAMES KING, OF SUCCASUNNA, NEW JERSEY.

Letters Patent No. 85,594, dated January 5, 1869.

IMPROVEMENT IN CHURNS.

The Schedule referred to in these Letters Patent and making part of the same.

To all whom it may concern:

Be it known that I, JAMES KING, of Succasunna, in the county of Morris, and State of New Jersey, have invented a new and useful Improvement in Churns; and I do hereby declare that the following is a full, clear, and exact description thereof, which will enable those skilled in the art to make and use the same, reference being had to the accompanying drawings, forming part of this specification, in which—

Figure 1 is a sectional view of the box, showing the dasher within.

Figure 2 is a similar view, when a circular box or can is used instead of a square box.

Figure 3 is a detail end view of the dasher.

Figure 4 is a top view of the dasher, when employed in a circular box or can, as in fig. 2.

Similar letters of reference indicate corresponding parts.

The object of this invention is to provide a simple and effective churn, and one which is easily cleansed.

It consists, in general terms, of a dasher of peculiar form, arranged to revolve at an incline with the vertical axis of the can or box containing it.

In the drawings—

A is a square box, having a cover, B.

The dasher consists of a short plane of wood, metal, earthen, or other suitable material, having its corners truncated or rounded, to permit its revolution in the box or can, and at the same time to present the maximum surface to act upon the cream.

It further consists in the application of two wings or auxiliary vanes, D, affixed with their planes at right angles to the plane of the part C, and making, longitudinally, an angle with the axis of revolution with the dasher, and with each other, as is better shown in fig. 1, where the dotted lines indicate the relative position of the wing hidden by the part C.

The lower end of the part C is provided with a stud, which sets in any suitable step-bearing.

The axis part, a, of the crank-handle E, passes

loosely through a hole extending obliquely through the box, as shown, and affording a bearing for the said part a.

When a square box is employed, its form prevents the dasher from actuating the cream to move in a circular current, and thus retard the production of butter; but when the dasher is used in a can or circular box, as shown at figs. 2 and 3, fixed vanes or strips, H, are employed to break such currents.

The end view of fig. 3 shows the metal socket in which the squared end of the axis a is inserted.

By withdrawing the crank-handle from the socket, and from the box, the dasher is left free to be lifted out and cleansed, which, from its construction, presents no cracks and complicated parts or openings to render the cleansing-operation difficult.

In the operation of the dasher, the part C agitates the cream with a violent fluctuation, which is immediately met by the next immersing wing D, and which sets up a counter-fluctuation, and at the same time parts the cream from the top obliquely downward, thus admitting the air into the extreme bottom of the cream, and aerating it thoroughly, which conduces to the rapid formation of butter.

The red outlines in fig. 4 indicate the position of the parts C and D, as the dasher revolves.

I am aware that churn-dashers have heretofore been arranged in a diagonal position with the churn, but this I do not claim.

What I do claim, and desire to secure by Letters Patent, is—

The dasher, consisting of the plane C and wings D, constructed as described, and provided with the detachable crank E, as herein set forth, for the purpose specified.

JAMES KING.
